US00D603750S

(12) **United States Design Patent**
Flanagan et al.

(10) **Patent No.:** **US D603,750 S**
(45) **Date of Patent:** **** Nov. 10, 2009**

(54) **DISPLAY DEVICE**

(75) Inventors: **Sean Flanagan**, Geneva (CH); **James Deen**, Scottsdale, AZ (US)

(73) Assignee: **Golf Flagstick Advertising (UK) Ltd**, London (GB)

(**) Term: **14 Years**

(21) Appl. No.: **29/294,770**

(22) Filed: **Jan. 25, 2008**

(30) **Foreign Application Priority Data**

Jul. 27, 2007 (GB) 4003778

(51) **LOC (9) Cl.** **11-05**

(52) **U.S. Cl.** **D11/166**

(58) **Field of Classification Search** D11/131, D11/166, 181-185; D10/109; D21/708, D21/793, 794; D26/51; 40/333, 584, 606.01, 40/606.03, 606.13, 606.14, 607.01, 607.04, 40/607.05, 607.11, 612; D20/10, 16, 17, D20/19, 39, 41, 43, 99; 116/173; 135/15.1

See application file for complete search history.

(57) **CLAIM**

The ornamental design for a display device, as shown and described.

DESCRIPTION

FIG. 1 is a perspective view from the front of the display device;

FIG. 2 is a front view thereof;

FIG. 3 is a rear view thereof;

FIG. 4 is a left side view thereof;

FIG. 5 is a right side view thereof; and,

FIG. 6 is a top view thereof.

In each figure the broken line drawing of a flag is for illustration purposes and forms no part of the claimed design.
